UNITED STATES PATENT OFFICE.

DAVID GENESE, OF BALTIMORE, MARYLAND.

CAP FOR MILK BOTTLES.

Application filed June 28, 1923. Serial No. 648,374.

To all whom it may concern:

Be it known that I, DAVID GENESE, a citizen of the United States, residing at Baltimore city, in the State of Maryland, have 5 invented new and useful Improvements in Caps for Milk Bottles, of which the following is a specification.

This invention relates to caps or stoppers for bottles, jars and the like and designed 10 particularly for closing milk and cream bottles.

The primary object of the invention is to provide a cap or closure of pasteboard or cardboard ordinarily used for this purpose 15 and having a disk contour with means of a positive character for applying and removing the cap or closure and centrally applied to the latter in such manner as to effectively close the aperture or slot through 20 which the improved means partially extends, to thereby prevent ingress to the contents of the bottle or jar or deleterious germs or any matter that would in the least injure or contaminate the contents of the bottle or jar with 25 which the improved cap or closure is used. A further object of the invention is to provide means in connection with a pasteboard or cardboard cap or closure for a bottle or jar that may be readily secured to the cap or 30 closure and having such positive fixed association with the latter as to permit repeated use of the cap or closure without liability of injury to the latter, and whereby the bottle or jar mouth or neck may be 35 closed after use of a portion of the contents of the bottle or jar. A still further object of the invention is to economize and generally improve the manufacture of caps or closures for milk bottles, jars and the 40 like by using a non-corrosive applying and removing means which is associated with the cap or closure and may be formed of metal, pasteboard, cardboard or other non-corrosive or neutral material with respect to 45 the contents of the bottle or jar and which also acts to reinforce the portion of the cap or closure to which it is applied.

With these and other objects and advantages in view, the invention consists in the 50 construction and arrangement of the several

parts of the different forms of the improved device which will be more fully hereinafter described and claimed.

In the drawing:

Fig. 1 is a perspective view of a bottle or 55 jar cap or closure, showing the improved gripping means applied and fixed thereto;

Fig. 2 is a similar view, showing the manner of inserting the improved gripping means through the center of the cap or 60 closure;

Fig. 3 is a bottom plan view of the cap or closure, showing the manner of securing the gripping means thereto;

Fig. 4 is an enlarged detail perspective 65 view of the improved gripping means;

Fig. 5 is a plan view of the blank from which the improved gripping means is formed;

Fig. 6 is a perspective view of a cap or 70 closure, showing a modification in the form of the gripping means;

Fig. 7 is an edge elevation of a cap or closure with the improved gripping means applied thereto and preferably formed of 75 pasteboard or cardboard; and

Fig. 8 is a transverse vertical section on the line 8—8, Fig. 7.

The numeral 5 in all of the forms of the improved gripping means as shown in the 80 drawings designates the cap or closure, which is in the form of a disk of suitable dimensions that may be varied in accordance with the mouth of the bottle, jar or other device to which it is adapted to be removably applied. The cap or closure 5 will be manufactured as usual by suitable cutting dies, and while it is preferred to use pasteboard or cardboard in the manufacture of the disk, cap or closure 5, it will be understood that any other material adapted for 85 this purpose may be used.

The invention particularly resides in a gripping device generally designated by the 90 numeral 6 and may be formed of metal, 95 pasteboard, cardboard or other material of a character that will not in the least contaminate or injure the contents of the bottle or jar to which the cap or closure having the improved gripping means may be 100

applied. For the purpose of illustration, let it be assumed that the improved gripping means as shown by Figs. 1 to 6, inclusive, is formed of metal, which is coated or tinned or may be made of sheet metal commercially known as tin and consisting of a base metal with a tin coating. Referring particularly to the form shown by Figs. 1 to 6, inclusive, the improved gripping means comprises a main body 7 of substantially rectangular form, as shown by Fig. 5, and having oppositely extending securing members 8 of less width than the body and formed with reduced or tapered extremities 9. The body is centrally bent or folded in a transverse direction, to provide side members 10 continuous with a top loop or roll bend 11, the members 8 depending from the body members 10 an equal distance and normally in parallel relation. Owing to the material difference in width of the securing members 8 and the body members 9, closing shoulders 12 are provided at each side of the securing members 8, and when the improved gripping means is shaped as shown by Fig. 4, these shoulders present a considerable bearing or covering projection at each side of the centrally located securing means or members. The roll or bend 11 at the top facilitates positive gripping of the improved device and also strengthens the general structure. In applying the improved gripping means as shown by Figs. 1 to 5, inclusive, the reduced extremities 9 of the securing members 8 are forced through a narrow slot or cut 13 formed in the center of the cap 5, and when the shoulders 12 are forced downwardly and held in close contact with the upper surface of the cap adjacent to opposite extremities of the narrow slot or cut 13, the securing members 8 are spread and bent flat in opposite directions against the underside of the cap, as shown by Fig. 3. When the gripping means is thus secured to the cap, the narrow slot, cut or puncture that may be formed by forcing the securing members 8 with their reduced extremities 9 through the cap is fully closed and covered and also filled, so that there are no openings or crevices through which deleterious germs or matter may enter the bottle or jar when the improved cap has been applied. When the improved gripping means has been applied and secured to the cap as just explained, there is ample projection thereof above the top of the cap, to facilitate grasping the same and removing the cap and also for subsequently reapplying the cap. When the improved gripping means is formed of metal and the securing members 8 with their reduced extremities 9 are bent over against the underside of the cap as shown by Fig. 3, it will be unnecessary to use any additional securing medium to retain the

improved gripping means in fixed relation to the cap or to prevent the same from working loose.

In Fig. 6 the improved gripping means will be essentially of the same structure as shown by Figs. 1 to 5, inclusive, with the exception that the upper bend or roll 11 is omitted and the body of the gripping means is formed of two thicknesses of metal, as at 14, the blank used in producing the form of the improved gripping means as shown by Fig. 6 having the body thereof doubled in length with respect to the body 7 as shown by Fig. 5. The object of this modification is to give a greater bearing extent of the improved gripping means in a transverse direction relatively to the top surface of the cap or closure 5.

In Fig. 7 the gripping means is of the same shape as shown by Fig. 5 without the bend or roll 11 at the top and is preferably formed of paper. The upwardly projecting portion of the gripping means in Figs. 7 and 8 has the two body members 15 drawn closely together in flat relation with the securing members 16 extending at right angles away therefrom and firmly fixed against the lower side of the cap or closure 5 by a suitable cementitious substance such as paraffin or a paste which will not in the least affect the contents of the bottle or jar to which the cap or closure may be applied. It is also proposed in fixing the securing members of the paper, pasteboard or cardboard form of the device as shown by Figs. 7 and 8 to subject the same to heat pressure after the cementitious matter has been applied, or a suitable coating of combined protective and cementitious substance may be applied over the lower side of the cap after the securing members 16 have been bent outwardly in opposite directions, to insure a positive retention of the paper, pasteboard or cardboard gripping means to the cap or closure. It will be understood that in applying this cementitious substance or whatever material that may be used and adapted for the purpose, the quantity thereof will be minimized and hardly perceptible when applied, and the mode of applying this cementitious material may be varied without in the least modifying the features of the invention. The paper, pasteboard or cardboard form of the improved gripping means as shown by Figs. 7 and 8 will be effective and cheaper in its application than the metal form hereinbefore described, but obviously would not be as durable as the metal form.

In all of the forms of the improved device one of the essential features of common construction therein is the shouldered bearing provision at opposite sides of the securing members to firmly engage the top of the cap or closure and prevent the im-

proved gripping means from being forced through the cap or closure a greater distance than is desired, particularly when forcing the cap or closure 5 having the improved gripping means applied thereto into the neck or mouth of a bottle or jar. The shoulders projecting equally on opposite sides of the securing members give an equal bearing pressure on opposite sides of the center of the cap or closure beyond the terminals of the slot, cut or puncture through which the securing members are inserted, and when the securing members with their reduced penetrating extremities are inserted 15 through the cap or closure and opened and bent flat in reverse directions against the underside of the cap or closure, the latter will be firmly pressed up against the shoulders and the cap or closure will thus be reinforced where the improved gripping 20 means is applied.

It will be understood that changes in the general proportions and dimensions of the disk or closure and the improved gripping 25 means may be adopted at will, and the thickness of the material of which the improved gripping means is formed may also be modified without departing from the spirit of the invention.

30 What is claimed as new is:

1. A cap or closure for milk bottles and the like, consisting of a disk having a central slot therethrough and a stiff gripping means comprising an upper gripping member of greater length than the length of the slot and provided with centrally disposed integrally formed depending securing members of less width than the length of the said gripping member and inserted through the 35 said slot and reversely bent against the underside of the disk, angular shoulders of equal length being formed at opposite sides of the securing members by the greater length of the gripping members relatively 40 to the securing members, said shoulders extending outwardly beyond the opposite terminals of the slot and drawn in tight bearing contact with the top of the disk by the reversely bent securing members to prevent 45 the gripping member from being forced through the disk and to cause the shoulders to close the ends of the slot.

2. A cap or closure for milk bottles and the like, consisting of a disk having a central slot and a gripping means constructed of doubled relatively stiff material having an upper gripping member of greater length 55 than the length of the slot and securing members integrally depending from the center of said gripping member and of less width than the length of the gripping member but equal in width to the length of the slot and inserted through the latter and closely bent against the underside of the 60 said disk, the gripping means having shoul-

ders provided at the lower portions on opposite sides of the securing members, said shoulders being drawn in tight engagement with the upper surface of the disk and closing over the ends of the slot when the securing members are bent against the underside 70 of the disk.

3. A cap or closure for milk bottles and the like, consisting of a disk having a central slot, and gripping means formed from a single piece of relatively stiff material intermediately bent to form an upper gripping member of greater length than the slot in the disk and lower centrally located reduced securing members continuous with the upper gripping member and inserted through the slot and bent against the underside of the disk, the reduced securing members completely filling the slot from end to end of the latter and the greater length of the gripping member providing projecting portions that are extended over and completely close the ends of the slot and tightly bear on the upper surface of the disk, the shoulders owing to the double construction of the gripping means presenting two thicknesses of material as a bearing means on the top of the disk beyond the terminals of the slot to lessen the liability of puncture or penetration of the disk by the said shoulders. 85

4. A gripping means blank for a cap or closure for milk bottles and the like, constructed of relatively stiff material and consisting of a body of enlarged dimensions with reduced securing members of less width than and extending equally from opposite sides of the said body and provided with converged extremities, the reduced securing members of less width than the body forming shoulders between the opposite side edges of the said securing members and the side edges of the body. 100

5. A gripping means for a cap or closure for milk bottles and the like, constructed of relatively stiff material and consisting of a body which is intermediately bent to provide parallel body members drawn closely together to form a gripping member and having centrally located integral securing members of less width than the length of the body members and provided with reduced terminals, shoulders being formed at the side edges of the securing members by the greater length of the body members relatively to said securing members and at right angles to the latter members. 110

6. A gripping means for a cap or closure for milk bottles and the like, consisting of an intermediate metal body which is centrally bent and the bent members drawn closely together in parallel relation to unitedly form a gripping member and each of the said bent members having a centrally located securing member integral therewith and of less width than the adjacent portion 125 130

of the body member, the securing member being also primarily closely drawn together in parallel relation and having shoulders formed at opposite side edges thereof at 5 right angles thereto, the upper doubled portion of the gripping member being formed with a top roll extending the full length thereof to facilitate positive gripping of the device and also to strengthen the general 10 structure of said latter device, combined

with a disk having a central slot through which the securing members are inserted and bent against the underside of said disk, the shoulders being tightly drawn against the upper side of the disk to close the ends 15 of the slot through which the securing members are passed.

In testimony whereof I have hereunto set my hand.

DAVID GENESE.
